(57) **CLAIM**

The ornamental design for an “electrical barbecue grill,” as shown and described.

DESCRIPTION

FIG. 1 is a front perspective of an electrical barbecue grill in its closed position.

FIG. 2 is a bottom perspective of the electrical barbecue grill shown in FIG. 1.

FIG. 3 is a top plan view of the electrical barbecue grill shown in FIG. 1.

FIG. 4 is a bottom plan view of the electrical barbecue grill shown in FIG. 1.

FIG. 5 is a left end elevation of the electrical barbecue grill shown in FIG. 1.

FIG. 6 is a front elevation of the electrical barbecue grill shown in FIG. 1.

FIG. 7 is a right end elevation of the electrical barbecue grill shown in FIG. 1.

FIG. 8 is a rear elevation of the electrical barbecue grill shown in FIG. 1.

FIG. 9 is a front perspective of the electrical barbecue grill of FIGS. 1–8 in its open position.

FIG. 10 is a right end elevation of the electrical barbecue grill shown in FIG. 9.

FIG. 11 is a left end elevation of the electrical barbecue grill shown in FIG. 9.

FIG. 12 is a front elevation of the electrical barbecue grill shown in FIG. 9.

FIG. 13 is a rear elevation of the electrical barbecue grill shown in FIG. 9.

FIG. 14 is a top plan view of the electrical barbecue grill shown in FIG. 9; and,

FIG. 15 is a bottom plan view of the electrical barbecue grill shown in FIG. 9.

The broken lines are included for the purpose of illustrating portions of the electrical barbecue grill that form no part of the claimed design.

1 Claim, 9 Drawing Sheets
